Primary Examiner — Cathron C Brooks(74) *Attorney, Agent, or Firm* — Birch, Stewart, Kolasch & Birch, LLP(57) **CLAIM**

The ornamental design for an infant sofa, as shown and described.

DESCRIPTION

FIG. 1 is a front perspective view of the infant sofa showing our new design;

FIG. 2 is a front view thereof;

FIG. 3 is a rear view thereof;

FIG. 4 is a left side view thereof;

FIG. 5 is a right side thereof;

FIG. 6 is a top view thereof;

FIG. 7 is a bottom view thereof; and,

FIG. 8 is another front perspective view thereof, but showing legs and a camera with lighting in broken lines.

The broken lines depict portions of the infant sofa that form no part of the claimed design.

1 Claim, 8 Drawing Sheets(56)
